GEORGE B. OWEN, OF WINSTED, CONNECTICUT.

Design No. 3,337, dated January 12, 1869.

DESIGN FOR A CLOCK-BELL STAND.

The Schedule referred to in these Letters Patent and making part of the same.

To all whom it may concern:

Be it known that I, GEORGE B. OWEN, of Winsted, Litchfield county, Connecticut, have invented a new and original Design for a Clock-Bell Stand; and I do hereby declare that the following is a full, clear, and exact description thereof, which will enable others skilled in the art to make and use the same, reference being had to the accompanying drawings, forming a part of this specification, in which—

Figure 1 is a face view of my improved clock-bell stand.

Figure 2 is a cross-section of the same.

Similar letters of reference indicate corresponding parts.

My invention has for its object to furnish an improved design for a clock-bell stand, which shall be simple, appropriate, and ornamental; and

It consists in the design hereinafter more fully described.

A represents the bell-stand, which is somewhat bell-shaped in its general form, as shown in figs. 1 and 2.

Around the base of the stand A is formed a beading, a¹, so made as to have somewhat the appearance of a twisted rope.

The outer surface of the body of the stand is formed with radial projections a², increasing in breadth and altitude from the highest part or centre to the base of the stand, as shown in fig. 1.

A hole is formed in the centre, for the attachment of the bell, and several holes are formed around its base for the screws, by which it is screwed in place.

Having thus described my invention,

What I claim as new, and desire to secure by Letters Patent, is—

The design for a clock-bell stand, herein set forth.
